UNITED STATES PATENT OFFICE.

EDWARD C. STERNAMAN, OF CHICAGO, ILLINOIS.

CALK FOR ATHLETIC SHOES.

Application filed February 27, 1925. Serial No. 11,932.

This invention relates to athletic shoes of that type which are provided with calks or spurs on the under side of the sole and heel to prevent slipping and afford a secure 5 ground foothold for the wearer; and the invention has been designed more especially as an improvement in athletic shoes of the kind usually worn by football players.

One object of my present invention is to 10 provide an improved calk-attaching means that will very strongly and rigidly secure the calks to the sole and heel, that will strongly resist side thrusts on the calks, that will be unaffected by the swelling of the 15 calks from moisture, and that will not destroy or impair the natural flexible quality of the sole, thus leaving the feet of the wearer unhampered by any excessive stiffness or rigidity of the sole produced by the calks 20 and their attaching means. Another object is to provide an improved form and structure of calk that will be strong and durable, serve as an efficient ground grip, and at the same time be less dangerous to players than 25 the sharp conical calks or spurs heretofore quite extensively used.

Other objects and attendant advantages of the invention will be apparent to persons skilled in the art as the same becomes better 30 understood by reference to the following detailed description, taken in connection with the accompanying drawing wherein I have illustrated one practical embodiment of the invention which, in hard service on the football field, has proved its efficiency for the 35 purposes stated.

In the drawings—

Fig. 1 is a side elevation of an athletic shoe equipped with my improved calks or spurs; 40 Fig. 2 is a bottom plan view of the same;

Fig. 3 is a fragmentary enlarged vertical section through a portion of the sole, one of the calks, and the calk-attaching means; and

Fig. 4 is a side elevation, and Fig. 5 a perspective view of an improved form of safety calk or spur.

Referring to the drawing, 5 designates as an entirety the upper of the shoe, 6 the outer sole, 7 the heel, and 8 (Fig. 3) an inner sole or sole cover slip.

9 designates each of a plurality of calks or spurs that are tapered throughout their entire length and are attached to and project from the bottoms of the sole 6 and heel

7. These spurs are all alike, and preferably consist of compressed fibre,—a material presenting an excellent combination of lightness, strength, and freedom from splitting tendencies. The calk 9 has a broad flat base which rests squarely against the bottom of the sole or heel, as clearly shown in Fig. 3; and 10 designates a metal collar tapered to correspond with the taper of the calk and snugly embracing the base portion of the latter. This collar has at its base an integral annular flange 11 that bears upon the sole or heel all around the base of the calk. 12 designates each of a group of nails that are driven through the flange 11 and the outer sole, or heel, and have their upper ends clinched and preferably countersunk in the upper surface of the outer sole, as shown at 13. The foot of the wearer is additionally protected against possible chafing by the 15 nails by means of the overlying inner sole or sole cover slip 8. Preferably, and as shown in Fig. 3, the nails 12 are not driven through the sole in a direction normal to the plane of the latter, but are driven in an oblique direction inclined toward the axis 20 of the calk 9. By driving the fastening nails in this manner, a more powerful and tenacious grip of the nails in the sole is obtained.

I am aware that a round calk or spur of uniform diameter throughout with an outwardly flaring base portion has heretofore been attached to a shoe sole by means of a tapered ring overlying the flaring base portion, and nails or screws passed through said ring and base portion into the sole. This construction has one serious fault, especially where the calk or spur is made of a material that will absorb moisture, since the moisture causes the calk or spur to swell, and this swelling loosens and tends to pull out the attaching nails or screws. Furthermore, my invention is structurally distinguished from the known construction referred to in that it employs a tapered collar embracing the tapered base of the calk, an annular flange bearing only upon the sole or heel of the shoe, and attaching nails which pass directly through the flange and into the sole or heel without going through the calk or spur itself. Hence, my attaching means are unaffected by swelling of the calk or spur. It will also be observed by reference to Fig. 3 that the nails 12 are driven at points sub-

stantially contiguous to the edge of the base of the calk. This binds the collar 10 very tightly against the calk, aided by the fact that the nails are driven in a direction toward the axis of the calk and prevents danger of the collar springing or bending locally away from the calk under a powerful side thrust on the latter, which otherwise might occur and cause the base of the calk to spring out of the collar or at least work loose in the latter.

One of the commonest means for attaching a calk or spur to the sole of a shoe consists of one or more nails driven through the entire length of the calk into the sole. Where such a fastening means is employed, wear on the tip of the calk soon exposes the head of the nail, and when walking on hard surfaces, like cement or concrete, the nail is driven further in through the sole and chafes the foot of the wearer; thus making such calks short-lived. The calk fastening means herein shown and described manifestly obviates this objectionable feature.

A very efficient arrangement or grouping of the calks or spurs to resist forward, rearward and flank thrusts is shown in Fig. 2, wherein it will be observed that the sole is equipped with two longitudinal rows of calks disposed respectively on opposite sides of the longitudinal median line of the sole; there being preferably three calks in each row, as shown. The heel 7 is equipped with three calks disposed thereon in triangular relation, and preferably with one of the calks on the rear of the heel with its axis substantially in the longitudinal median line of the heel, and the other two located forwardly and on opposite sides respectively of said rearwardly located calk.

The described arrangement on both sole and heel is very effective, especially when used with the tapered conical calks or spurs shown. Manifestly, an inward flank thrust causes one longitudinal row on the sole to bite the ground, and an outward flank thrust causes the other longitudinal row to similarly bite the ground. This flank resistance is augmented by the two forward calks on the heel. Again, the triangular disposition of the heel calks enables the minimum number of calks to be used to secure a sufficiently broad support to prevent either forward and rear or side tipping. The described grouping of the calks on both the sole and heel is particularly efficient in withstanding and resisting side rocking movements of the shoe; and this is of large practical importance in the direction of preventing accidental spraining or breaking of the ankle of the

wearer in the rough scrimmages that frequently occur on the football field.

The sharp pointed conical form of calk shown in Figs. 1 and 2 is disapproved by some players on the ground that it is unduly dangerous in the rough scrimmages that frequently occur on the football field, sometimes producing ugly wounds. With a view to obviating this objection and providing a calk that will be both efficient and much safer, I have designed the improved form of tapered calk illustrated in Figs. 4 and 5. This calk is preferably made of the same material (compressed fibre) as the conical calk shown, but consists of a section of a solid cylinder 14 having two opposite sides thereof flattened and inclined downwardly toward each other as shown at 15 but not intersecting, thereby creating a wedge-shaped structure having a narrow blunt ground-contacting edge or surface 16 that has a length equal to the full diameter of the calk body. This calk employs the same fastening means as those previously described, for which purpose it is formed with a round tapered base 17 to receive and fit the flanged collars 10, 11. Manifestly this improved calk is much blunter, and hence correspondingly less dangerous than the comparatively sharply pointed calks illustrated in connection with Figs. 1 and 2. Its bilateral wedge shape, however, gives it ample gripping effect on the ground in play, and otherwise affords practically all the advantages of the pointed conical calk, with a much higher factor of safety.

Finally, by independently fastening the several calks to the sole of the shoe, and locating them as near the edges of the latter as is practicable, the natural flexibility of the sole is not seriously impaired or restricted, and hence the shoe may be worn with practically the same degree of comfort as an ordinary shoe.

I claim:—

A calk structure consisting of a spur body tapered toward the outer end at its base and having a flat inner surface, a collar including a tapered portion snugly encircling the base of the spur body to confine the latter against withdrawal from the collar and an annular securing flange formed on the inner edge of the tapered portion and extending radially thereof to locate its inner face in the same plane as the said flat inner surface of the spur body, said flange having a series of openings for receiving securing elements.

EDWARD C. STERNAMAN.
